CLAIM

The ornamental design for a hose reel, as shown and described.

DESCRIPTION

FIG. 1 is a top perspective view of a hose reel design showing my new design.

FIG. 2 is a front view of the hose reel.

FIG. 3 is a rear view of the hose reel.

FIG. 4 is a left view of the hose reel.

FIG. 5 is a right view of the hose reel.

FIG. 6 is a top view of the hose reel.

FIG. 7 is a bottom view of the hose reel; and,

FIG. 8 is a bottom perspective view of the hose reel.

The broken lines in the drawings depict portions of the hose reel that form no part of the claimed design.
